MACHINE FOR MAKING BATS

Otto R. Winter, Cincinnati, Ohio, assignor to The
Upson Company, Lockport, N. Y., a Corpora-
tion of New York

Application January 22, 1930. Serial No. 422,684

6 Claims. (Cl. 154—29)

My present invention relates to machines for making batting as a continuous process from cotton, jute, animal hair and many of the other familiar fibrous materials commonly used in structures of this kind and the invention has for its object to provide a simple, efficient, and durable machine of this character embodying certain advantages and improvements relating generally to the feeding of the stock in a manner that insures a thickness at the edges equaling that at the center; to the means for conveying the bat after it leaves the forming mechanism, and to provisions in connection with the latter whereby sewing, to obtain a quilting effect, is facilitated.

To these and other ends the invention resides in certain improvements and combinations of parts, all as will be hereinafter more fully described, the novel features being pointed out in the claims at the end of the specification.

In the drawings:

Fig. 1 is a side elevation of approximately one-half of a bat forming machine constructed in accordance with and illustrating one embodiment of my invention, the same being the feed end of the machine;

Fig. 2 is a similar view of the delivery end of the machine in continuation of Fig. 1;

Fig. 3 is an enlarged view in central vertical section through the sewing section of the machine;

Fig. 4 is an enlarged detail of certain parts of the sewing mechanism shown in Fig. 3;

Fig. 5 is a detailed plan view of the conveyor apron for the formed bat;

Fig. 6 is a section therethrough, enlarged, taken on the line 6—6 of Fig. 3;

Fig. 7 is an enlarged horizontal section through the feeding chamber taken substantially on the line 7—7 of Fig. 1;

Fig. 8 is an enlarged section of the feed delivery chute taken substantially on the line 8—8 of Fig. 1;

Fig. 9 is a plan view of a section of bat such as my machine produces with part of the top liner broken away, and

Fig. 10 is a section, enlarged, on the line 10—10 of Fig. 9.

Similar reference numerals throughout the several views indicate the same parts.

An understanding of the operation and objects of my machine can best be understood after an understanding is had of the article which it is its object to produce.

Referring to Figs. 9 and 10, I there show a

strip of batting such as is used to insulate the walls of buildings and the floors and ceilings, although the making of carpet linings and similar objects is within the scope of the capabilities of the machine. This particular product consists of 60 an interior felt-like center or core 1 consisting of the materials hereinbefore named having sewed to it at lateral intervals a number of paper strips 2. The strips are in pairs on opposite sides of the bat in alignment so that they assist 65 in holding the body of the bat in shape. On each side of the structure so far described, there is applied with an adhesive, such as glue or silicate of soda, paper liner strips 3 and 4 which adhere tenaciously to the bat and particularly to the 70 sewed paper strips 2. My machine assembles and combines all of these elements as a continuous process.

Referring now more particularly to Figs. 1 and 2, I will describe briefly the whole machine and 75 the course of the stock therethrough to the point of delivery and later describe more in detail the particular elements in which my invention resides. A hopper, indicated generally at 5, is provided with openings 6 into which the raw stock 80 from the bales is shovelled through doors or openings 6. It contains feeding or picking mechanism that preliminarily disintegrates the lumpy mass. It is then drawn from a chest 7 by means of a suction pipe 8 connected with a blower 9 to a 85 feeding chamber 10. A conveying and picking apron 10a carries it from the bottom of this chamber and dumps it into a chute 11 from which it falls in finely divided form by gravity upon a horizontal feeding apron 12. 13 is an exhaust 90 for lint. The apron 12 delivers to a Garnett element 13a which in turn delivers to forming rolls 14. Issuing from the forming rolls the bat passes between driven rolls 15 that guide it over a short table 16 upon an apron 17 running over rolls 18 95 endlessly. The strips 2 are applied from supply rolls 19 and then sewed to the bat immediately by a sewing mechanism 20. Passing thence through pressure rolls 21, the liners or outer paper sheets 3 and 4 are applied to the upper 100 and lower sides as drawn from supply rolls 22 and 23 and after trimming at 24, the finished bat is drawn up an incline 24a. 25 and 26 are the pasting or adhesive applying units for the liners. 105

At the end of the incline, as shown in Fig. 2, is a swatching mechanism indicated generally at 27, which delivers it in bales 28 but which need not be further described.

Now describing in detail the chute 11 and associated mechanism, shown particularly in Figs. 7 110

and 8; it will be seen that the mouth or delivery end of the chute is over the apron 12 above mentioned, which apron runs over rollers 29 journaled in a trough-like member having upwardly extending side flanges 30. The belt 12 fills substantially the entire width of the trough-like member between the flanges 30, and these flanges 30 define the width of the bat which is formed on the apron 12 and delivered thereby to the Garnett picker 13a.

It has been found in actual practice that when the chute 11 which delivers the stock to the apron 12 is throughout its length of only the same width as the bat which it is desired to form, there is a tendency to deliver more stock to the center of the bat than to the edges thereof, which tendency seems to be due to a retarding effect caused by the side walls of the chute upon the stock passing therethrough. Consequently, the stock delivered to the apron is noticeably thinner at the edges than at the center, with the result that an improper bat is formed when it is desired to make a bat of uniform thickness throughout its width.

It has also been found in actual practice that this tendency to form a bat thin at the edges is overcome if the chute throughout the major portion of its length be made somewhat wider than the width of the bat to be formed, the chute being tapered or contracted at its delivery end to the width of the bat desired. Such a construction is shown clearly in Fig. 8, where it will be seen that the side walls of the chute are tapered or inclined inwardly and downwardly at 32 to the bottom edge 31, which forms the delivery mouth, this delivery mouth being substantially equal in width to the space between the upstanding flanges 30 which is the width desired for the bat. Above the tapered portions 32, however, the side walls of the chute may be substantially straight and parallel with each other, as shown, and here the chute is materially wider than the width of the bat to be formed. The lines 33 projected upwardly from the delivery mouth show the width of the mouth in comparison to the width of the main portion of the chute above the mouth. The conveyor 10a delivers stock to the upper end of the chute substantially throughout the entire width thereof. It is found in practice that with this construction the bat material delivered to the apron 12 is of substantially uniform thickness throughout the entire width of the bat, the edges of the bat as indicated at B being as thick as the center of the bat. Thus there is produced a bat having the desired characteristics of uniform thickness, notwithstanding the retarding effect of the side walls of the chute on the stock passing therethrough.

Referring now to Figs. 1 and 3, it has heretofore been the usual practice to provide a table of substantial length beyond the forming rolls 14, over which table the bat is thrust by the driving rolls 15. It is found in practice, however, that at this stage of its manufacture the bat is frequently not sufficiently strong to be thrust over a table of any substantial length, and likewise it is not strong enough to be pulled over the table by pull rolls. Hence, according to the present invention, there is provided a conveyor apron at this point which receives the bat almost immediately after it issues from the feed rolls 15 and which conveys it forwardly without pushing or pulling strain.

Preferably this conveyor apron comprises a plurality of laterally spaced belts 36, as best shown in Figs. 5 and 6. The spaces between the

belts are in alinement with the paper strips 2 which are applied to the top and bottom of the bat and also in alinement with the sewing needles 38, so that these needles may sew through the strips as the bat moves along without sewing through or otherwise interfering with the conveyor apron.

The conveyor apron, as shown particularly in Figs. 3 and 4, receives the bat at a point close to the forming rolls and carries it forwardly to and beyond the sewing mechanism, so that before the bat leaves the conveyor apron, the strips 2 have been sewn to it and the bat is then sufficiently strong to continue its further travel without the aid of this apron.

Means is preferably provided for sprinkling a chemical (for example, a granular salt) upon the bat for the purpose of making it fireproof or verminproof. This means may comprise a hopper 39, shown especially in Fig. 3, having at its mouth a sprinkler or agitator 40 arranged to deliver the chemical onto the bat at a point subsequent to the attachment of the bottom liner 4 and prior to the attachment of the upper liner 3. Since the chemical is sprinkled upon the top of the bat, it is desirable to provide means for causing it to permeate thoroughly the texture of the bat material, and there is accordingly provided an agitator 41 (Figs. 3 and 5) driven by a chain 42 from an independent motor 43. This agitator 41 is preferably in the form of a rotary member having one or more fins (two being shown in the drawings) which, upon rotation of the member, contact with the under surface of the bat, the impact causing a slight shaking of the bat which shakes the chemical into the bat material and causes it to permeate such material thoroughly.

While one embodiment of the invention has been disclosed, it is to be understood that the inventive idea may be carried out in a number of ways. This application is therefore not to be limited to the precise details shown, but is intended to cover all variations and modifications thereof falling within the spirit of the invention or the scope of the appended claims.

I claim as my invention:

1. In a bat making machine, the combination with bat forming mechanism, of a plurality of laterally spaced belts for carrying a bat forwardly from said forming mechanism, and sewing mechanism, for sewing through said bat in the space between said belts, and substantially perpendicular to the plane of said bat.

2. In a bat making machine, the combination with a Garnett element, of means for feeding bat stock thereto, forming rolls associated with said Garnett element for receiving a partially formed bat therefrom, sewing mechanism for sewing said bat, transversely through the plane thereof, and travelling apron mechanism for carrying a bat forwardly from said forming rolls to and beyond said sewing mechanism, said apron mechanism comprising a plurality of laterally spaced belts arranged one on either side of said sewing mechanism.

3. In a bat making machine, the combination with bat forming mechanism, of a plurality of laterally spaced belts for carrying a bat forwardly from said forming mechanism, means for applying sheet material to said bat in alinement with the space between said belts, and sewing mechanism operating in the space between said belts for sewing through said bat and sheet ma-

terial, substantially perpendicular to the plane thereof.

4. In a bat making machine, the combination with conveying means for moving a bat, of mechanism for applying a chemical to said bat, and means for agitating the bat during the travel thereof and subsequent to the application of chemical thereto to cause said chemical to permeate said bat thoroughly.

10 5. In a bat making machine, the combination with conveying means for moving a bat, of mech-

anism for sprinkling a chemical upon said bat, and agitating means impacting said bat to cause said chemical to permeate the bat.

6. In a bat making machine, the combination with conveying means for moving a bat, of mechanism for sprinkling a chemical upon said bat, and agitating means including a rotatable member beneath said bat for impacting the under side thereof to cause said chemical to permeate the bat.

OTTO R. WINTER.
